ROOFING AND SIDING

John A. Topping, Bronxville, N. Y.

Application February 20, 1935, Serial No. 7,337

8 Claims. (CL 108—7)

This invention relates to shingles or strips for use in covering roofs or sides of buildings, and particularly to asphalt saturated and coated, granular surfaced, felt base shingles or strips.

5 A general object of the invention is to improve that type of asphalt saturated and coated, granular surfaced, felt base shingle or strip which is provided with an overlay coating on at least a portion of the exposed portion of the strip for 10 the purpose of increasing the weight and rigidity of the exposed portion as well as improving its weather-resisting qualities.

As heretofore usually made shingles or strips which have had an overlay or second coating 15 have been so initially prepared that, in cutting the shingle or strip from the sheet, the cut has intersected both coatings. This has proved to be objectionable in that the two coatings have frequently tended to separate at the raw free edge 20 thus exposed when the shingle or strip has been placed on the roof or the side of a building and exposed to extremes of weather.

Of course one of the primary purposes of providing two coatings on a shingle or strip and cutting through the two coatings to form the butt 25 end is to cause the shingle or strip to have the appearance of having a thickened butt somewhat similar to the butt of a wooden shingle. Because, however, of the objections to the laminated thick 30 butt produced by cutting through two coatings, attempts have been made to produce the thick butt effect in other ways as, for example, by the process known as double-dipping or seal-dipping, which is a relatively slow and expensive process.

35 An important object of the present invention, therefore, is to provide an improved roofing or siding strip which will have the desired weight, rigidity and weather-resisting qualities of its exposed portions and which will at the same time 40 produce the desired thick butt effect without the necessity for cutting through both coatings, a particular aim of the invention being to facilitate the production by machinery of thick butt 45 simulating shingles which are substantially free from the objections to the machine-made thick butt shingles heretofore produced.

The invention also aims to produce a shingle simulating a thick butt shingle which can also be utilized with equal facility to produce imitation 50 brick siding.

Other objects and important features of the invention will appear from the following description and claims when read in connection with the accompanying drawings in which

55 Figure 1 is an elevation of a roof or side wall

covered with the novel shingles or strips of the present invention;

Figure 2 is a detail plan showing one method of producing these strips from roll roofing;

Figure 3 is a section on the line 3—3 of Figure 2;

Figure 4 is a section on the line 4—4 of Figure 1;

Figure 5 is a transverse section showing a method of making a modified form of the invention with a plurality of overlays on each strip;

Figure 6 is a section showing another modification;

Figure 7 is a plan view of an individual strip having an overlay with an irregular contour;

Figure 8 is a section on the line 8—8 of Figure 7;

Figure 9 is an elevation of a roof or side wall covered with strips of the type illustrated in Figure 7, and

Figure 10 is a modification in which the coating and surfacing are confined to the exposed portions.

As hereinabove suggested, in practicing the novel method of the present invention and producing the novel shingle or strip, the entire sheet of asphalt saturated felt base roofing 2 is first coated with a layer of asphalt 4 over its entire surface and is then provided with a surfacing of mineral or artificially prepared granules 6, also over the entire surface in the preferred manner of practicing the invention.

If the roofing is of such a width that four of the shingles or strips may be cut from its width there will then be superimposed upon the original surfaced coating four strips of overlay coating 8 in the form of two pairs of strips, each pair being spaced from the outer edge of the sheet a distance equal to the head lap of the shingle, the strips of each pair being spaced from each other twice the distance of the desired exposure of the original surfaced coating at the lower edge of the strip or shingle. It will be obvious that the two pairs of strips 8 are spaced from each other a distance equal to twice the desired head lap.

The strips of overlay coating 8 having been applied to the sheet in any suitable manner as, for example, by rollers dipping into a supply of the coating material, these strips are then surfaced with any suitable granular surfacing material 10, which is preferably of a color different from the surfacing material 6 so as to provide a contrast at the lower end of the exposed part

of the shingle or strip where the original surfacing 6 is still exposed.

The sheet is now ready for slitting to form the individual strips or shingles. It will be obvious 5 that in a sheet such as shown in Figure 2 where four shingles are to be formed across the sheet it will be necessary to slit the sheet along three lines, two of the slits 12 and 14 being formed between the strips 8 of each of the pairs of overlay 10 strips and the third slit 16 being along the median line of the sheet, that is, half way between the two pairs of overlay strips 8.

If it is desired to make shingle strips having a plurality of tabs formed by cutouts 18 in the exposed portions of the strips, these cutouts will 15 preferably be formed as a part of the slitting and strip-forming operation.

In Figure 1 is shown a roof made up of three tab strips having cutouts 18 formed in any suitable manner, these strips having each a band or margin 20 at its lower edge where the original surfacing 6 is exposed. This, by contrast with the surfacing 10, gives a shadow effect at the lower edge of each strip or tab and thus, with 25 the overlay coating and surfacing, adds to the impression of butt thickness.

It will also be noted that the slots 18 expose a part of the original surfacing. Thus the shadow effect of the slots is also emphasized. Moreover, 30 when it is desired to make these strips of such proportions that they can be used to produce imitation brick siding, by suitable coloring of the original surfacing 6, the slots 18 and the exposed margins 20 of the original surfacing will produce 35 the effect of mortar joints.

It will also be noted that in causing the overlay coatings 8 to cover all of the exposed portion of the strip or shingle except the margin at the lower edge, a gage line is provided at the upper 40 edge of the exposed portion of the shingle or strip which facilitates the laying of the shingle or strips with the desired uniform head lap, the course next above being laid with its lower edge abutting the upper edge of the overlay coating 8.

45 In Figure 5 is shown a modification of the invention in which, instead of a single overlay coating, a plurality of overlay coatings is provided, each surfaced before the succeeding coating is placed thereon and each preferably set back from its under coating a short distance to emphasize 50 the thick butt simulating effect. In the Figure 5 modification there is provided, besides the original coating 8, two successively set back coatings 22 and 24.

55 In Figure 6, instead of providing a coating at the lower margin of the shingle or strip of the same thickness as that on the head lap portion, this coating is preferably made thicker than that on the head lap portion in any suitable manner 60 as, for example, by leaving the space, which will coincide with the space between the two overlay coats, uncoated when the sheet is originally coated whereby none of the original surfacing 6 will adhere to this space, and then filling this 65 space up to the level of the first overlay coating 8 when said overlay coat is applied, surfacing the thick section thus made with surfacing material, either of the same character or different from that applied to the first overlay coat, and then 70 providing a second overlay coat 26, as shown in Figure 6.

75 Where it is desired to relieve the monotony of too uniform strip designs, this can be effected by giving the lower edge of the overlay coating an irregular contour, as shown particularly in Fig-

ures 7 and 9. Such an irregular contour of substantially one-dimensional character can be given by cutting back portions of the edge of the coating applying roll so that these are not effective to apply the coating up to a uniform straight edge. 5 The margins of the roll can also be so shaped as to give two-dimensional irregularities in contour such as shown in Figure 7, or these two dimensional irregularities can be produced by superimposing a second overlay coating upon the first 10 overlay coating and using a roller with an irregular edge for each overlay application. As in the other forms of the invention, the margin 20 will preferably consist of the original coating 4 and surfacing 6, whereas the overlay coating indicated 15 as 28 in Figure 7 will be the part that will be given the irregular contour 30.

In the modification of the invention shown in Figure 10, the coating and surfacing, both the original coating and surfacing and the overlay, 20 are confined to the exposed portion of the shingle or strip, the unexposed portion being merely the asphalt saturated felt base, which may be covered with any suitable non-sticking material such as powdered soapstone.

25 From the foregoing description it will be obvious that the invention provides not only an improved shingle or strip construction in which the exposed edge is cut only through a single coating and not through laminae which may 30 separate when exposed to the weather, but that the invention lends itself to machine manufacture and to the ready production of artistic effects.

What I claim as new is:

1. A roofing or siding strip comprising a felt base saturated with waterproofing material, a coating of asphalt covering the entire upper surface of said base and having embedded therein a surfacing of granular material, and a substantial thickening and weight imparting overlay coating of asphalt having embedded therein a surfacing of granular material, said overlay coating covering all of that portion of the initially coated roofing or siding strip which is to project beyond 45 the next higher course, except a narrow thick-edge simulating margin along the lower edge thereof.

2. A roofing or siding strip comprising a felt base saturated with waterproofing material, a 50 coating of asphalt covering the entire upper surface of said base and having embedded therein a surfacing of granular material of one color, and a substantial thickening and weight imparting overlay coating of asphalt having embedded 55 therein a surfacing of granular material of another color, said overlay coating covering all of that portion of the initially coated roofing or siding strip which is to project beyond the next higher course, except a narrow thick-edge simulating margin along the lower edge thereof.

3. A roofing or siding strip comprising a felt base saturated with waterproofing material, a coating of asphalt covering the entire upper surface of said base and having embedded therein 65 a surfacing of granular material, and a substantial thickening and weight imparting overlay coating of asphalt having embedded therein a surfacing of granular material, said overlay coating covering all of that portion of the initially 70 coated roofing or siding strip which is to project beyond the next higher course, except a narrow margin along the lower edge thereof, the color of said narrow strip so contrasting with that of the remainder of the exposed part of the roofing 75

or siding strip as to produce a thick butt shadow effect.

4. A roofing or siding strip comprising a felt base saturated with waterproofing material and having therein cutouts to form shingle simulating tabs, a coating of asphalt covering the entire upper surface of said base and having embedded therein a surfacing of granular material of one color, and a substantial thickening and weight imparting overlay coating of asphalt having embedded therein a surfacing of granular material of another color, said overlay coating covering all of that portion of the roofing or siding strip which is to project beyond the tab ends of the next higher course, except a narrow thick-edge simulating margin along the lower edge thereof.

5. A roofing or siding strip comprising a felt base saturated with waterproofing material and coated with asphalt over its entire upper surface, granular surfacing material embedded in said asphalt coating, and a substantial thickening and weight imparting granular surfaced overlay coating covering that portion of the upper face of said strip which is to project beyond the next higher course, except a narrow thick-edge simulating margin along the lower edge thereof, the lower edge of said overlay being irregular in contour.

6. A roofing or siding strip comprising a felt base saturated with waterproofing material and coated with asphalt over its entire upper surface, granular surfacing material embedded in said asphalt coating, and a substantial thickening and weight imparting granular surfaced overlay coating covering that portion of the upper

face of said strip which is to project beyond the next higher course, except a narrow margin along the lower edge thereof, the lower edge of said overlay showing two-dimensional irregularities in its contour.

5.

7. A roofing or siding strip comprising a felt base saturated with waterproofing material, a coating of asphalt covering at least the exposed portion of said strip when laid upon the roof and having embedded therein at least in the exposed portion thereof in the roof, a surfacing of granular material and a substantial thickening and weight imparting overlay coating of asphalt having embedded therein a surfacing of granular material, said overlay coating covering all of that portion of the initially coated roofing or siding strip which is to project beyond the next higher course, except a narrow thick-edge simulating margin along the lower edge thereof.

8. A roofing or siding strip comprising a felt base saturated with waterproofing material, a coating of asphalt covering at least the lower part of the exposed portion of said strip when laid upon the roof and having embedded therein, at least in that part of said coating which is exposed when the overlay coating has been applied, a surfacing of granular material, and a substantial thickening and weight imparting overlay coating of asphalt having embedded therein a surfacing of granular material, said overlay coating covering a part of said initial coating and all of that portion of the roofing or siding strip which is to project beyond the next higher course, except a narrow thick-edge simulating margin along the lower edge thereof.
